S. KIEN

SECURING MEANS FOR RAILS

Filed July 15, 1926

UNITED STATES PATENT OFFICE.

STANISLAUS KIEN, OF ROCHESTER, NEW YORK.

SECURING MEANS FOR RAILS.

Application filed July 15, 1926. Serial No. 122,595.

The present invention relates to securing means for rails, and an object of the invention is to provide a metallic rail tie which will do away with the ordinary wooden tie and will be strong and durable in construction, while, at the same time, adapting itself readily to embedment in a plastic material or for containing a plastic material which will firmly hold the tie in position. Another object of the invention is to provide a novel means of securing the rails to the tie so as to firmly hold the rails in place against accidental disconnection from the tie. Still another object of the invention is to provide an improved rail securing means which may be readily connected and disconnected from the tie, so that the parts entering into the same may be used again after the disconnection of the rail and the tie.

To these and other ends, the invention consists of certain parts and combinations of parts, all of which will be hereinafter described: the novel features being pointed out in the appended claims.

25 In the drawings:

Fig. 1 is a perspective view showing two ties and the rails secured thereto in accordance with this invention, one of the ties being designed for use on the rails between the joints and the other being designed for use on the rails at the joints;

Fig. 2 is an enlarged fragmentary section through the tie and the rail;

Fig. 3 is a detail plan view of one of the ties with the rails and securing devices removed for the purpose of showing the pockets in the tie;

Fig. 4 is a perspective view of the device for securing the inner side of the rail;

Fig. 5 is an end view of the device for securing the outer side of the rail, showing a fragment of the tie;

Fig. 6 is a view showing the two wedge members in connected relation; and

Fig. 7 is a perspective view of the ends of two rails.

Referring more particularly to the illustrated embodiment of the invention, 1 indicates a railroad tie which in this instance is formed from a single metal casting with marginal flanges 2 depending about the same in order to provide a pocket substantially throughout the length and width of the tie in which may be received concrete or other plastic material which will add to the weight of the tie. In fact the tie as a whole may be

embedded in concrete so that the flange 2 extends into the bed. The top surface of the tie may be provided with transverse depressions or grooves 3, the width of each of which is substantially equal to the base of an ordinary railroad rail.

The rail may be of any suitable construction and in this instance it has the ordinary base piece 4, the web 5 and the tread 6. In order to dispense with the usual tie plates the tread portion 6 at one end of each rail may be projected as at 6^a beyond the web 5 and the base 4, while the opposite end may be cut away at 6^b in the tread portion so that the web and the base project beyond the tread to receive the projecting portion 6^a of another rail. A lip 6^c may be extended from the projecting portion 6^a and be received in a pocket 6^d formed in the opposite end of another rail. That end of the rail which has the pocket 6^d may have a pocket 4^a formed in the underside thereof while a lip 4^b may be extended from the opposite end of the web to fit in a pocket 4^a of an adjacent rail. In this way, when the ends of two rails are brought together, the upper and lower parts of the rails are tied together. At the same time the break in the joint is bridged by the tongue 6^a and as a consequence the wheel does not strike the joint in a way to hammer or pound in passing over the same.

In order to hold a rail or rails to the tie, a securing means is provided which preferably employs one or more pockets formed in each tie on the inner side of each rail. These pockets have each an enlarged portion 7 which is located in the tie in that portion on which the rail rests. This enlarged portion has a portion extending therefrom which has its upper part 8 reduced with reference to its lower part 9, the latter being of a width substantially equal to the width of the portion 7. A rail securing device is employed which embodies a head 10 with a depending anchoring portion which has an enlarged end 11 and a reduced portion 12. The enlarged end has a width which is substantially equal to the width of the enlarged portion of the pocket 7 while the reduced portion 12 has a width which is substantially equal to the restricted portion 8 of the pocket. The head 10 projects from opposite sides of the anchoring portion and has an inclined portion 13 for cooperation with the upper surface of the base 4 while the opposite side is horizon-

tal as at 14 for cooperation with the upper surface of the tie. This securing device which is designed for one side of the rail, preferably the inner side, has its enlarged portion 11 first introduced into the portion 7 of the pocket and then shifted laterally in said pocket so that the portion 11 will occupy the portion 9 of the pocket below the reduced portion 8. It is preferred to provide one of these devices for each tie except at the joints. Each rail may also be notched at intervals at 15 to receive the reduced portion 12 of each of the securing devices.

15 For holding the opposite or outer base of the rail, the tie is provided with a pocket 16 to one side of the portion 3 on which the rail rests. This pocket is deeper than the pocket on the inner side of the rail and has a lateral extension formed by a portion 17 of less depth than the portion 16 but of the same width and a reduced portion 18 leading upwardly from the portion 17 and intersecting the seat 3. The securing device for the outer side of the rail has a top portion 19 with an inclined portion 20 for engaging the base of the rail. Depending from this top portion to one side of the inclined portion is an anchoring portion comprising a reduced portion 21 substantially the width of the reduced portion 18 of the pocket and an enlarged portion 22 substantially the width of the extension 17 of the pocket 16. After the rail has been seated on the seat 3 and a securing device 10 has been engaged with the inner side thereof, the securing device 19 has its anchoring portion introduced into the pocket 16 and then shifted laterally so that it enters the extensions 17 and 18, the enlarged portion 22 occupying the portion 17 and the reduced portion 21 occupying the reduced portion 18 of said extension.

15 A holding means is employed for holding the securing device in engagement with the outer side of the rail. This holding means, in this instance, comprises two cooperating wedge members 23 and 24. The wedge member 23 rests on top of the tie and has a depending portion 25 which has one face 26 vertically arranged to cooperate with one wall of the pocket 16 while the opposite face 27 is inclined to the vertical and to the surface 26. The inner face of this member 23 is also bevelled at 28 to cooperate with the bevelled face 29 on the securing member 19. The wedge member 24 has a bevelled rib 30 on one side arranged to operate in a vertical groove or recess 31 in the pocket 16 below the extension 17 to prevent the turning of the member 24. This bevelled rib cooperates with a bevelled surface 32 on the anchoring portion of the securing member 19 while the opposite sides of this wedge member 24 has a bevelled surface 33 for cooperating with

the bevelled surface 27 on the depending portion 25 of the wedge member 23.

An adjustable connection is provided between the two wedge members 23 and 24 whereby the wedge member 24 may be drawn upwardly to force the depending portion 25 firmly against the outer side of the slot 16 and to force the securing member 19 inwardly in firm engagement with the base of the rail 4. This adjustable connection, in this instance, embodies a bolt 34 which is mounted to turn loosely in the wedge member 23 and is adapted to engage a nut 35 secured against turning in a pocket in the underside of the wedge member 24. It is apparent that the turning of this screw 34 in one direction will elevate the wedge member 24, forcing the extension 25 of the wedge member against the outer wall of the pocket 16 and forcing the securing device 19 inwardly over the rail base 4. The turning of the screw in the other direction causes the wedge member 24 to lower until eventually the screw disconnects from the wedge member 24 and may with the wedge member 23 be withdrawn from the pocket 16, the wedge member 24 then occupying a position below the lower edge of the securing member 19 so that the latter may be shifted laterally out of engagement with the rail base 4. If desired, the outer edge of the base 4 may be provided with a plurality of notches 36 in which the reduced portion 21 of the securing device 19 may enter. Preferably the reduced portion of the extension 18 extends into the seat 3 of the rail so that the wall of the reduced portion will not interfere with the movement of the securing device into firm engagement with the rail base 4. It is preferred to use only one of the securing devices 19 with its cooperating wedge members on each tie piece, but where a joint occurs two of such members may be employed for engaging the rail on opposite sides of the joint. The notches in the rail base on the inner and outer sides thereof should be sufficiently wide to permit the expansion and contraction of the rail.

115 In the use of the invention the ties are laid preferably by filling the same with cement, although they may be laid directly in the usual bed or in a bed of cement. The securing devices on the inner side of the rails are then placed in position and the rails are then placed on the seats 3, so that the inner sides of their bases 4 are overhung by the securing devices 10. The wedge members 24 may now be introduced into the pocket 16, and, thereafter, the securing devices 19 may have their anchoring portion fitted in the extensions of the pocket 16. The wedge members 23 are then introduced into the pocket 16 and the bolts are then engaged with the nuts 35 so as to draw the wedge members upwardly in order to force the

wedge members 23 in binding engagement with the pockets 16 and the securing devices 19 in binding engagement with the rail. It is apparent that this arrangement not only 5 secures the rails to the ties without the use of tie plates, but permits the rails to be readily disconnected from the ties. There is no danger of any of the parts working loose as would be the case with the ordinary spike 10 employed for securing rails.

What I claim as my invention and desire to secure by Letters Patent is:

1. The combination with a railroad tie formed with a pocket having an extension to one side provided with a reduced upper portion, of a rail securing device having an anchoring portion with a reduced portion fitted in the reduced portion of the pocket extension and an enlarged portion received in said extension below said reduced portion, and means detachably secured in that portion of the pocket to one side of the extension for holding said rail securing device in the extension and in cooperation with the rail supported on the tie, said means embodying cooperating wedge members adjustably connected.

2. The combination with a railroad tie formed with a pocket having an extension to one side provided with a reduced upper portion, of a rail securing device having an anchoring portion with a reduced portion fitted in the reduced portion of the pocket extension and an enlarged portion received in said extension below said reduced portion, and means detachably secured in that portion of the pocket to one side of the extension for holding said rail securing device in the extension and in cooperation 30 with the rail supported on the tie, said means embodying two wedge members having cooperating wedge faces and each having wedging engagement with said locking member.

3. The combination with a railroad tie formed with a pocket having an extension to one side provided with a reduced upper portion, of a rail securing device having an anchoring portion with a reduced portion 45 fitted in the reduced portion of the pocket

extension and an enlarged portion received in said extension below said reduced portion, and means detachably secured in that portion of the pocket to one side of the extension for holding said rail securing device in the extension and in cooperation with the rail supported on the tie, said means embodying cooperating wedge members, one of which cooperates with a wall of the pocket opposite the securing member and 55 also with said securing member and the other of which cooperates with the first mentioned wedge member and with the securing member, and means for adjustably connecting said wedge members.

4. The combination with a railroad tie formed with a pocket having an extension to one side provided with a reduced upper portion, of a rail securing device having an anchoring portion with a reduced portion 60 fitted in the reduced portion of the pocket extension and an enlarged portion received in said extension below said reduced portion, and means detachably secured in that portion of the pocket to one side of the extension for holding said rail securing device in the extension and in cooperation with the rail supported on the tie, said means 65 embodying cooperating wedge members, one of which cooperates with a wall of the pocket opposite the securing member and also with said securing member and the other of which cooperates with the first mentioned wedge member and with the securing member, and means for adjustably connecting said wedge members comprising a screw.

5. The combination with a rail having two pockets formed therein each of said pockets having an extension to one side thereof formed with a reduced portion, one 70 of said pockets having its main portion in that part of the tie beneath the portion on which the base of the rail rests and the other having its main portion to one side of said portion of the tie on which the base 75 of the rail rests, and means detachably arranged in the main portion of the last mentioned pocket for holding the securing device within the extension of said pocket.
